ROTARY SLIP ELEVATOR

Cecil Ware, Houston, Tex.

Application May 3, 1949, Serial No. 91,168

7 Claims. (Cl. 24—263)

1

This invention relates to a rotary slip elevator.

An object of the present invention is to provide a rotary slip for handling pipe in a well bore and which includes means for handling the slip, in a convenient manner, in making up or breaking out the string of pipe while it is being lowered into or withdrawn from the well bore.

The invention includes means whereby the slip segments will be automatically released from the pipe, and maintained so released, upon elevation of the pipe with manually operable means for releasing the slip from said inactive position whereby the segments may engage about the pipe and seat in the rotary table in position to suspend the pipe, from said table, in the well bore.

Other objects and advantages will be apparent from the following specification, which is illustrated by the accompanying drawings, wherein:

Figure 1 is a side elevation of the slip partly in section showing the slip handling equipment associated therewith in vertical section.

Figure 2 is a horizontal sectional view taken on the line 2—2 of Figure 1.

Figure 3 is a vertical sectional view taken on the line 3—3 of Figure 1;

Figure 4 is a horizontal sectional view taken on the line 4—4 of Figure 1; and

Figure 5 is a fragmentary cross-sectional view taken on the line 5—5 of Figure 1.

Figure 6 is a detail view partly in section on a somewhat enlarged scale, showing structural details of operating parts of the mechanism.

Referring now more particularly to the drawings, the numeral 1 designates the rotary table having a downwardly converging slip seat 2 in which the slip is mounted when in pipe-supporting position.

In the present illustration the slip is shown as being composed of segments 3 whose inner sides are provided with pipe-engaging teeth 4. These teeth define a cylindrical surface so as to fit closely about a pipe supported by the slip; however, the outer surfaces of the segments 3 have their lower portions tapered downwardly to conform to the contour of, and to fit snugly within, the seat 2, whereby the segments will be wedged between the pipe and said seat.

At the upper end of the slip there are the opposed, arcuate yokes 5, 5, which are hinged together by means of the hinge pin 6. These yokes are fitted through slots in the upper ends of the segments provided to receive them and are bolted to the segments by means of suitable bolts as 7.

2

In the present illustration, four segments are shown, two being mounted on each yoke.

The hinge pin 6 is retained in place by an enlarged head 8 thereon, whose lower end rests on the hinged ends of the yokes and whose lower end of pin 6 is threaded to receive a retaining nut 9, which is threaded onto the lower end of the hinge pin.

The hinge pin extends upwardly from the head 8 and its upper end works through a link 10, which has a pivotal bearing on the upper end of said pin and is retained in place by means of a nut 11 screwed onto the upper end of the pin.

Secured on the rotary table in any preferred manner there is a supporting frame 12. As shown, this frame is secured to the rotary table by means of bolts 13, 13, although it may be secured to the table in any selected manner. This frame 12 also includes outwardly extended parallel arms 14, 14, whose inner ends may be secured to the frame proper in any preferred manner, as by welding. Preferably these arms 14 are upwardly and outwardly inclined as shown in Figure 1, and secured between their outer ends

20 there is an upstanding anchor 15; also, in the present illustration, there is an upstanding web 16 extending transversely across the frame 12 between said arms, as illustrated in Figures 1 and 2.

25 There is a beam which includes oppositely disposed, upstanding side members or guides 17, 17, whose inner sides have opposed longitudinal grooves 18, 18; and these side members are connected, at their outer ends, by the cross-bar 19, which may be secured to said side members in any preferred manner.

30 The inner end of the web 16 is formed into a transversely disposed bearing 20 of a length considerably greater than the thickness of said web, as shown in Figures 2 and 3, and the lower ends of the side members 17 are fitted against the ends of the bearing 20, and an axle pin 21 is fitted through the bearing 20 and its ends are reduced and fitted through bearings in the lower ends of the side members 17 and have retaining nuts 22, 22 on the ends thereof to retain said side members in place.

35 Between the side members 17 there is an anchor block 23, which is provided with side tenons which extend into the grooves 18, and the lower end of this block is bifurcated, providing side arms between which the link 10 extends; and this link is pivotally connected to the block 23 by means of a transverse pin 24 which extends 40 through them.

3

There is a cylinder 25 whose outer end is pivotally connected to the upper end of the anchor 15 and whose inner end is provided with a bearing 26 secured therein. There is a plunger 27 in the cylinder, and connected to it there is a plunger rod 28 which works through the bearing 26 and whose inner end is formed with a bearing through which the pin 24 also works.

In the present illustration there is a coiled spring 29 within the cylinder around the rod 28 and interposed between the bearing 26 and the plunger 27.

Mounted between the side members 17, near their upper ends, there is a yoke 30 whose ends are reduced, forming tenons which fit into the grooves 18. A rod 31 is slideable through the cross-bar 19 and has an outer end head as 32 to limit its downward movement, and its lower end is threaded into the yoke 30. A coiled cushioning spring 33 surrounds the rod 31 and is interposed between the cross-bar 19 and the yoke 30, thus forming a cushion for said yoke.

The inner end of the yoke is downwardly turned, forming a bumper 34, and pivotally connected to the other end of the yoke there is a grip member 35 whose pivoted end is provided with a downwardly extended hook 36, and the outer side of the anchor block 23 is provided with a corresponding hook 37 which is engageable with the hook 36 as will be hereinafter explained.

With the slip in the rotary table seat and in position to engage and support a pipe extending through the slip into the well bore, the parts will be in the position shown in Figure 1, and upon elevation of the pipe the slips will be elevated out of the seat 2 but will be maintained clamped around the pipe by means of a wedge 38 which wedges between the extensions 39, 39 of the arcuate yokes 5 as best seen in Figure 6. This wedge is fastened in the lower end of a vertical rod 40, which extends up through an aligned bearing in the link 10. This rod is vertically movable in said bearing but is provided with an elongated side notch 41 through which a retaining pin 42 extends, said pin being mounted in the link 10 and projecting into said notch to limit the movement of rod 40.

Upon elevation of the pipe, as above indicated, the slips will move with the pipe substantially vertically, and the link 10 and block 23 will move upwardly also, and as they move upwardly the beam, above described, will be moved toward the pipe and toward vertical position. The inner end of the cylinder 25 will also be moved vertically, and the spring 29 will be placed under compression. Eventually, the upper end of the rod 40 will strike the bumper 34, and the wedge 38 will be moved downwardly from between the extensions 39. The spring 33 will act to limit the upward movement of the yoke 30 and will also act as a shock absorber; also, the hook 37 will come into inter-engagement with the hook 36, and upon release of the wedge 38, as above explained, the slip segments will be free to open.

It will be noted from an inspection of Figures 1 and 3 that there are the opposed release arms 43, 43 pivotally mounted on the beam side members 17 with their upper ends free, and secured to said side members there are the leaf springs 44, 44 whose outer free ends press inwardly against said release arms.

The release arms are so positioned that as the slip is elevated the extensions 39 will pass

4

in between them, and said arms will be moved outwardly, thus placing the springs 44 under tension. When the slip has reached the limit of its upper movement, and the wedge 38 is released, as hereinabove explained, the release arms 43, 43, pressing inwardly against the extensions 39, 39 will cause the yokes 5, 5, and the slip segments carried thereby, to swing open, and the pressure of the spring 29 will assist in moving the beam and slip away from the pipe. The elevator will move outwardly into the position indicated in Figure 1, but the pipe-supporting structure will be held in elevated position by the hook 36.

When it is desired to lower the slip into the rotary table seat 2 to again support the pipe the grip member 35 may be pulled upwardly to release the hook 36 from the hook 37 of the anchor block, thus permitting the slip to descend into said seat 2 and the parts will then assume their original position as indicated in Figure 1. As the parts assume their final position, as indicated in Figure 1, the lower end of the wedge 38 will strike against a yieldingly mounted bumper 45, which will drive said wedge securely between the extensions 39. This bumper 45 is mounted on the upper end of a rod 46 which works through a bearing in an inwardly extended flange 47 of the frame 12, and between this flange and the bumper 45, and surrounding the rod 46, there is a coiled spring 48 provided to absorb the shock when the wedge strikes the bumper but which is of sufficient strength to cause the wedge to be driven between said extensions.

On the lower end of the rod 46 there is a nut 49 to prevent displacement of the rod 46.

It is to be understood that what is now considered to be a preferred form of the invention has been illustrated and described. It is of course obvious that various mechanical changes may be made in the actual construction of the equipment. The drawings and descriptions are by way of illustration only and not by way of limitation, while the broad principle of the invention will be embodied in the appended claims.

What I claim is:

1. A device for handling a rotary slip comprising, a supporting frame adapted to be mounted on a rotary table, a beam upstanding from the frame, an elevator block movable along the beam, a slip composed of segments, opposed arcuate yokes which are hinged together and which support the slip segments, a link connecting the yokes to the block, said yokes having extensions at their pivoted ends, wedge means connected with said link and positioned to wedge between said extensions to hold the slip segments in closed position, said elevator block being movable upwardly on the beam, upon elevation of the slip, to move the beam toward vertical position, a bumper on the beam positioned to release the wedge means from between the extensions, upon elevation of the slip, to allow the slip segments to open.

2. A device for handling a rotary slip comprising, a supporting frame adapted to be mounted on a rotary table, a beam upstanding from the frame, an elevator block movable along the beam, a slip composed of segments, opposed arcuate yokes which are hinged together and which support the slip segments, a link connecting the yokes to the block, said yokes having extensions at their pivoted ends, wedge means connected with the elevator block and positioned

to wedge between said extensions to hold the slip segments in closed position, said elevator block being movable upwardly on the beam, upon elevation of the slip, to move the beam toward vertical position, a bumper on the beam means cooperable with the wedge means and positioned to engage the bumper to release the wedge means from between the extensions, upon elevation of the slip, to allow the slip segments to open, and means on the frame positioned to drive the wedge means between said extensions when the slip has reached the limit of its downward movement.

3. A device for handling a rotary slip composed of segments and comprising, a supporting frame adapted to be mounted on a rotary table, a beam upstanding from the frame, an elevator block movable along the beam, a slip composed of segments, opposed arcuate yokes which are hinged together and which support the slip segments, a link connecting the yokes to the block, said yokes having extensions at their pivoted ends, wedge means connected with said link and positioned to wedge between said extensions to hold the slip segments in closed position, said elevator block being movable upwardly on the beam, upon elevation of the slip, to move the beam to substantially vertical position, a bumper on the beam positioned to release the wedge means from between the extensions upon elevation of the slip, to allow the slip segments to open, and means on the beam engageable with said extensions to positively open said segments upon release of the wedge means.

4. A device for handling a rotary slip composed of segments and comprising a supporting frame adapted to be mounted on a rotary table, a beam upstanding from the frame, a supporting element movable along the beam, a slip composed of segments, opposed arcuate yokes which are pivoted together and which support the slip segments in position to open and close about a pipe, means connecting the yokes to said supporting element, means connected with said connecting means and normally locking the yokes in closed position, said supporting element being movable upwardly on the beam, upon elevation of the slip, to move the beam into substantially parallel relation with the vertical axis of the slip, means on the beam positioned to release the locking means, upon elevation of the slip, to allow the slip segments to move to open position.

5. A device for handling a rotary slip composed of segments and comprising a supporting frame adapted to be mounted on a rotary table, a beam upstanding from the frame, a supporting element movable along the beam, a slip composed of segments, opposed arcuate yokes which are pivoted together and which support the slip segments in position to open and close about a pipe, means connecting the yokes to said supporting element, means connected with said connecting means and normally locking the yokes in closed position, said supporting element being movable

upwardly on the beam, upon elevation of the slip, to move the beam into substantially parallel relation with the vertical axis of the slip, means on the beam positioned to release the locking means, upon elevation of the slip, to allow the slip segments to move to open position, and means on the elevator and operative against the yokes to positively open the slip upon release of said locking means.

10 6. A device for handling a rotary slip composed of segments and comprising, a supporting frame adapted to be mounted on a rotary table, a beam upstanding from, and pivoted to, said frame, a supporting element movable along the beam, a slip composed of segments, opposed arcuate yokes which are pivoted together and on which the slip segments are mounted, a link connecting the yokes to the supporting element, means carried by the link and adapted to lock the yokes, and segments carried thereby, about a pipe to be supported by the slip, said supporting means being movable upwardly on the beam, upon elevation of the slip, to move the beam into substantially parallel relation with the vertical axis of the slip, latch means on the beam engageable with said supporting means to hold the slip in elevated position, means on the beam positioned to release said locking means to allow the slip segments to move to open position, means on the beam arranged to operate the yokes to open the segments upon release of the locking means, and means mounted on the supporting frame and connected with said supporting element and effective to move the beam away from said vertical axis.

35 7. A device for handling a rotary slip comprising, a supporting frame to be mounted on a rotary table and forming an adapter, a beam upstanding from, and pivoted to, said adapter, a slip composed of segments, opposed arcuate yokes pivoted together and adapted to support the slip segments, a supporting element movable along the beam, a link to which the yokes and the supporting element are connected, means for locking the yokes and slip about a pipe whereby upon elevation of the pipe the slip and supporting element will be elevated along the beam, release means on the beam positioned to release the locking means to allow release of the slip from the pipe, and releasable latch means on the beam adapted to engage said supporting element and maintain the same, and the slip, elevated.

CECIL WARE.
